THOMAS PHILLIP PARKER, OF WHEELING, WEST VIRGINIA, ASSIGNOR TO WHEELING STEEL CORPORATION, OF WHEELING, WEST VIRGINIA, A CORPORATION OF DELAWARE

MITER FOR SHEET METAL CORNER BEADS

Application filed August 6, 1930. Serial No. 473,468.

This invention relates to corner miters for corner beads and screeds, and more particularly to a miter-joint forming connection between meeting angularly-related metal corner beads, or screeds.

The primary object of the invention is to provide a miter-forming device for use in angles formed at the adjacent ends of right-angled related corner beads of so-called bull-nose type, as about uncased window and door openings in walls, wall niches, and the like, which device complements said beads and forms at the angle between the latter a continuous exposed surface.

15 A further object is to provide, in association with the adjacent right-angularly sheared end of right-angularly related corner beads of that type commonly employed as a trim and plaster gauge in external angles of uncased wall openings, a simple and inexpensive connection or attachment whereby is formed between such beads a close-fitting miter-like joint.

20 In describing the invention in detail, reference is herein had to the accompanying drawings, in which—

Figure 1 is a view in front elevation illustrating the invention applied to the adjacent ends of angularly related corner beads disposed about a window opening;

25 Figure 2 is a sectional elevation of the same, the section being taken on line 2—2, Fig. 1, with the plaster applied to the inner side wall and to the window sill;

30 Figure 3 is a similar section on line 3—3, Fig. 1;

Figure 4 is an inner face perspective view of the corner miter;

35 Figure 5 is an outer face elevation of the same; and

Figure 6 is a section on line 6—6, Fig. 5.

Referring to said drawings, 1 and 2 designate right-angularly related sheet-metal corner beads of the bull-nose type commonly employed in the outer corner angles formed by meeting interior plastered walls of buildings, such beads being used both as a protective trim and as a depth gauge for the plaster. As herein shown, said corner beads 1 and 2 are applied to the faces of the wall defining a

window opening, but it will be understood that this disclosure is merely illustrative, such beads and the present invention being applicable in numerous other places.

One of said beads, as the bead 1, is attached to the wall, or to the lath 3 of such wall, with an end thereof, or a portion of such end, more or less closely abutting the lath 4 of the adjacent wall defining the window opening, as shown in full lines in Fig. 3 and as is indicated in dotted lines in Fig. 1, said end being cross-sheared at a right angle to the length of the bead. The associated bead 2 has fitted closely within that end thereof which forms an angle with said bead 1 the tongue portion 5' of a false corner miter 5. Said miter is formed of a single piece of sheet metal and comprises, in addition to the tongue 5', a body 5" of arcuate form in cross section which conforms both in width and shape to the exposed face of the head portion of the bead 2 for forming a continuation of the latter, as shown in Figs. 1 and 2.

The tongue 5', which is slightly tapered toward its end, is shaped to conform to the curvature of the inner wall of the head portion of the bead and is adapted for having its opposite lateral edges received within the channels 6 formed interiorly of and at opposite sides of said head portion. Further, said tongue is inwardly offset with respect to the body 5" of the miter, thereby to form a shoulder 7 against which the adjacent end of the bead 2 may seat, or abut, and which, therefore, limits the extent to which the miter may telescope with respect to said bead. The body 5" terminates at the end opposite the tongue 5' in a diagonally inclined edge 8 which is curved to conform substantially to the shape of the thereby engaged surface of the head of the bead 1 for forming with the latter a line joint of miter form, as is most clearly shown in Fig. 1. Said edge 8 is inclined at an angle of substantially 45 degrees relative to the axial line of the miter, and, having a slight concave curvature, is thus adapted to seat closely upon the head of the bead 1. Manifestly, the miter 5 is applied to the bead 2 prior to mounting the latter in

place, and said miter constitutes means for spacing said bead 2 relative to the bead 1.

The miter described provides an extremely simple and inexpensive form of device whereby, without alteration of the form of the ends of the corner beads as the latter are furnished by the manufacturer, two angularly related beads may be joined for forming a joint of miter form and appearance.

10. What is claimed is—

1. In combination with adjacent angularly related corner beads, a miter-joint forming connection comprising a body substantially corresponding in size and contour with the face portions of the heads of said beads and terminating at one end in a diagonally inclined edge for conformably seating upon the head of one of said beads, and an integral tongue formed on the opposite end of said body occupying telescoped relation to the adjacent end of the head of the other of said beads.

2. In combination with adjacent angularly related corner beads, a miter-joint forming connection comprising a body substantially corresponding in size and contour with the face portions of the heads of said beads and terminating at one end in a diagonally inclined edge which is curved to adapt it to seat conformably upon the head of one of said beads, and a tongue formed integrally on the opposite end of said body, said tongue being receivable within the head of the other bead.

3. A miter for sheet metal corner beads comprising a sheet metal body of arcuate form in cross section, and a tongue formed on one end of said body and occupying inwardly offset relation to the latter, the opposite end of said body terminating in a diagonally inclined edge.

4. A miter for sheet metal corner beads comprising a body of arcuate form in cross section having at one end thereof a tongue-like extension which is inwardly offset with respect to said body, forming a shoulder, said body having its opposite end inclined at an angle of approximately 45 degrees to the axial line thereof.

5. In combination with corner beads disposed in right angular relation in a wall opening, one of said beads having an end thereof occupying abutting relation to one of the defining walls of the opening and the other of said beads having its adjacent end occupying spaced relation to said one bead, of a connection interposed between said ends and comprising a body substantially corresponding in size and contour with the face portions of the heads of said beads and terminating at one end in a diagonally inclined edge which conformably seats upon the head of said one bead, the opposite end of said connection being received within the head of the said other bead.

6. In combination with corner beads disposed in right angular relation in a wall opening, one of said beads having an end thereof occupying abutting relation to one of the defining walls of the opening and the other of said beads having its adjacent end occupying spaced relation to said one bead, of a connection interposed between said ends and comprising a body substantially corresponding in size and contour with the face portions of the heads of said beads and terminating at one end in a diagonally inclined curved edge which conformably seats upon and complements the head of said one bead in the formation of a false miter joint, the opposite end of said connection being reduced to form a tongue which is received within the head of the said other bead.

In testimony whereof, I affix my signature.

THOMAS PHILLIP PARKER.
